DESIGN FOR A HEATING-STOVE.

Design No. 13,606, dated February 13, 1883.

UNITED STATES PATENT OFFICE.

H. CLAY BASCOM AND FRANCIS RITCHIE, OF TROY, NEW YORK, ASSIGNEES
TO BERGSTROM BROTHERS & CO., OF NEENAH, WISCONSIN.

DESIGN FOR A HEATING-STOVE.

SPECIFICATION forming part of Design No. 13,606, dated February 13, 1883.

Application filed December 30, 1882. Term of patent 14 years.

To all whom it may concern:

Be it known that we, H. CLAY BASCOM and FRANCIS RITCHIE, citizens of the United States, residing in the city of Troy, in the county of Rensselaer and State of New York, have jointly invented and produced a new and original Design for Heating-Stoves, of which the following is a specification, reference being had to the accompanying print, cut, or engraving of a stove having said new design.

The design for the vase A consists of the body *a*, having the side ornament, *a'*, stem *b*, and scroll-form lateral handles *c*, each having the middle block ornament, *c'*, standing top ornament, *c''*, and pendent bottom ornaments, *c'''*, and all shaped and arranged together, substantially as shown in the accompanying print.

The design for the top section, B, consists of the cap-plate C and lower top plate, D, all shaped, ornamented, proportioned, and arranged together so as to present substantially the same appearance as is represented in the accompanying engraving.

The design for the cap-plate C consists of the lower fillet, *d*, having thereon the series of upwardly-pointing ornaments *d'*, and the upper convexly and concavely curved portion, *e*, having the series of ornaments *e'*, all shaped and arranged together substantially as shown in the accompanying cut.

The design for the top plate, D, consists of the upper concave molding, *f*, the lower fillet, *g*, and the intermediate convexly-curved portion, *h*, having the series of downwardly-pointing ornaments *i* along the upper edge, the series of upwardly-pointing ornaments *j* along the lower edge, and the middle series of ornaments, *k*, connected with the ornaments *j* and alternating with the ornaments *i*, and all shaped and arranged together substantially as represented in the accompanying engraving.

The design for the door-frame plate E consists of the ornamental outline form of its outer edge, *l*, the ornament *m*, and lateral scroll ornaments *n* at the top, and the ornaments *o* at the bottom, all shaped and arranged substantially as shown in the aforesaid print.

The design for the base-section F consists

of the top plate, *G*, bottom plate, *H*, and intervening side plate, *I*, and door-plate *J*, all shaped, ornamented, and arranged together so as to present substantially the same appearance as is represented in the aforesaid cut.

The design for the side plate, *I*, consists of the upper series of alternately different downwardly-pointing ornaments *p*, connected at top by ornaments *q*, the lower series of connected ornaments, *r*, and the end ornament, *s*, all shaped and arranged together substantially as shown in the aforesaid print.

The design for the front door, *J*, consists of the oblong rectangular panel *t*, having the series of oblong upright apertures *t'* and row of upwardly-pointed ornaments *t''*, in connection with the outer border portion, *u*, having the corner ornaments, *u'*, and middle, top, and bottom ornaments, *u''*, all shaped and arranged together as shown in the aforesaid cut.

The design for the legs consists of the body portion *v*, convex horizontally and curved concavely from top to bottom, and having the middle sprig ornament, *w*, and the downwardly curved and pointed border ornament *x*, with top scrolls, *y*, all shaped and arranged together substantially as represented in the accompanying engraving.

What we claim as our joint invention is—

1. The design for the vase A, composed of the parts *a a' b c c' c'' c'''*, all shaped and arranged together as set forth.

2. The design for the top section, B, composed of the parts C and D, all shaped, ornamented, proportioned, and arranged together as described.

3. The design for the cap-plate C, composed of the parts *d d' e e'*, all shaped and arranged as set forth.

4. The design for the top plate, D, consisting of the parts *f g h i j k*, all shaped and arranged together as described.

5. The design for the door-frame plate E, consisting of the parts *l m n o*, all shaped and arranged together as set forth.

6. The design for the base-section F, composed of the parts *G H I J*, shaped, ornamented, and arranged together as set forth.

7. The design for the side plate, I, composed of the parts $p\ q\ r\ s$, all shaped and arranged together as described.

8. The design for the front door, J, consisting of the parts $t\ t'\ t^2\ u\ u'\ u^2$, all shaped and arranged together as set forth.

9. The design for the legs, composed of the parts $v\ w\ x\ y$, all shaped and arranged together as described.

In testimony whereof we hereunto set our hands, in the presence of two subscribing witnesses, this 12th day of December, 1882.

H. CLAY BASCOM.
FRANCIS RITCHIE.
